UNITED STATES PATENT OFFICE

GREGORIO JOHN BOONZAIER, OF HARLESDEN, ENGLAND

CAM DEVICE

Application filed October 6, 1928, Serial No. 310,768, and in Great Britain October 13, 1927.

This invention involves an improved cam device which is primarily designed for use in connection with carburetors for internal combustion engines. The cam may be employed in a carburetor for the regulation of, for example, a jet-control needle, but it is also applicable to other purposes. For example, it may be used as a master cam for facilitating the commercial manufacture of cams for any purpose.

Other objects and features of the invention will appear from the following description, referring to the accompanying drawings, in which:—

Fig. 1 is an elevation of a cam according to the invention;

Fig. 2 is a detail of the cam mechanism;

Fig. 3 is a part-sectional elevation of one form of carburetor equipped with the invention, and

Fig. 4 is a plan thereof.

Referring more particularly to the drawings, the carburetor body, in the construction illustrated, consists of an intake pipe A, Fig. 3, flanged at its upper end for attachment to the intake manifold of the engine, and having in its lower end, which is the only air intake of the carburetor, a jet or fuel nozzle A² which is supplied from an annular float chamber B arranged around the intake pipe and rigidly connected with it and provided with a petrol pipe R, Fig. 4, said chamber containing an annular float B¹.

Around the jet A² and at or near its upper end is inserted a variable iris diaphragm choke D, of which the various apertures, from a "pin hole" to "wide open," are always circular, with the jet centrally located therein. This diaphragm is operated by a partial rotation of its mount by means of a spider D' and a metal tube O which extends upwards and through the cover E of the intake pipe.

The diaphragm aperture around the jet is controllable externally by means of a lever N which engages the tube O. This diaphragm operating lever is slidably attached to the main throttle lever L by a slide rod M¹. Means are provided for temporarily decreasing the diaphragm aperture by withdrawing the slide rod M¹ by means of an auxiliary

accelerator rod M² attached to the lever N and so increasing suction around the jet when a richer mixture is required than the synchronized setting with the throttle L² would otherwise allow. On release of the lever N the tension spring M³ returns the rod M¹.

The jet can be bored to any convenient size and the fuel supply regulated by means of a threaded needle valve F Fig. 3. This needle is also synchronized with the throttle by being operated from an adjustable cam K through a quadrant H and a pinion G, which pinion is threaded on to the needle valve F. The cam K consists of a pivoted body, which pivot engages in the split bush end of the throttle spindle L¹ and is held in the desired tilted position by a bolt or set screw L³. The helix of the cam K is variable and is constituted by a flexible metal blade of steel or other suitable material K¹, Fig. 1. This cam helix-blade operates the quadrant H, Fig. 4, which in turn engages the threaded pinion G. At the cam end the quadrant H is provided with a slotted swivelling washer H², Fig. 2. The slotted washer is retained in position in the circularly recessed end of the quadrant by a cap plate H¹ and pivot set screw H³. The blade of the cam is variable between its extreme position K³, Fig. 1, by means of set screws K², six in number. The fuel supply can therefore be regular or irregular relative to the throttle movement and choke diaphragm apertures. The needle valve F is prevented from rotating by a square or suitably shaped end sliding through a guide P so that any rotation imparted to the pinion G reciprocates the needle valve F, the pinion G being prevented from rising by a spacing washer between it and the guide P, or by other suitable means. Clearly the cam might act directly on the valve or through other suitable mechanism.

While the cam above described has been shown as applied to a carburetor, it will be clear that its use is not confined to this particular purpose.

What I claim is:—

1. A cam device comprising a U-shaped base, a flexible strip carried between the arms of the U, and means mounted in the

arms of said **U**-shaped base for adjusting the contour of said strip.

2. A cam device comprising a **U**-shaped base, pairs of adjustable screws carried by the arms of the **U**, and a flexible strip supported between said screws.

3. A cam device comprising a **U**-shaped base, a flexible member carried between the arms of said **U**-shaped base with its walls in parallelism therewith, and adjustable screws carried by said arms for engagement with the walls of said strip for varying the contour thereof.

4. A cam device comprising a **U**-shaped base, a flexible member carried between the arms of said **U**-shaped base with its walls in parallelism therewith, and adjustable screws carried by said arms for engagement with the walls of said strip for varying the contour thereof, said strip projecting beyond said arms for engagement by a follower.
